ROY E. TOMLINSON, OF MONTCLAIR, NEW JERSEY, AND HENRY H. HUNGERFORD, OF CHICAGO, ILLINOIS, ASSIGNEES TO NATIONAL BISCUIT COMPANY, OF NEW YORK, N. Y., A CORPORATION OF NEW JERSEY.

BISCUIT-CONTAINER.

1,311,541.

Specification of Letters Patent. Patented July 29, 1919.

Application filed June 28, 1918. Serial No. 241,932.

To all whom it may concern:

Be it known that we, ROY E. TOMLINSON and HENRY H. HUNGERFORD, citizens of the United States, the former residing at Mont- 5 clair, in the county of Essex and State of New Jersey, and the latter residing at Chicago, in the county of Cook and State of Illinois, have invented certain new and useful Improvements in Biscuit-Containers, of 10 which the following is a specification.

Our invention relates to the formation of metal containers for holding biscuits or the like food products, and the object of our invention is to provide containers which may 15 readily and economically be manufactured and filled, which shall be effectively sealed against air, gas and moisture and which may readily and easily be opened without the use of any instrument. One of the particular 20 points which we have in contemplation is the provision of such containers which may be used for military service overseas, and which will be entirely proof against poison gas and at the same time be readily opened 25 by a simple manipulation. We provide such a container by slitting the metal blank for a sufficient distance and then soldering a metal strip, known as a taggers tin, over the slit. The blank is formed into an elongated container, in which the crackers or 30 other goods are inclosed, the ends of the package being suitably closed and the slit referred to covered over by the metal strip, extending partway around the container, 35 midway between its ends. It is desirable to have the slit extend across what may be termed the top of the container (in the case of a rectangular container), and partway down the two sides, the metal being scored 40 from the ends of the slit to the bottoms of the sides. The metal strip or taggers tin is soldered at its edges so as to make the slit air- and gas-tight, the strip being, however, 45 easily detachable by outward pull on one end thereof, which end is left unfastened. When the taggers tin is pulled off, the package may easily be broken open along the 50 scored lines, the two halves of the container swinging open about the unscored bottom portion in alinement with the slit and the scored lines, as a hinge.

In order that a clearer understanding of our invention may be had, attention is hereby directed to the accompanying drawings

forming part of this application and illustrating one embodiment thereof. In the drawings, Figure 1 represents a perspective view of a closed container embodying our invention, Fig. 2 is a view partly in elevation and partly in longitudinal section of 60 the closed container, Fig. 3 is a side elevation of the container in partly open position, and Fig. 4 is a cross section taken on line 4-4 of Fig. 2.

Referring to the drawings, the container 65 represented generally at 1 is formed of tin or other suitable metal, the body portion of the container being suitably closed as by soldering the same along a longitudinal seam 2, shown at the bottom of the container. 70 The ends are closed by suitable closures 3, 3, which may be secured to the body portion in any suitable manner to make an air- and gas-tight closure. For example, flanged end 75 pieces may be set in the ends of the body portion of the container and the double wall thus formed rolled outwardly in well-known manner, to form the beads 4, 4.

The slit 5 extends entirely across the side 6 of the container, which may be termed the 80 top side, and partway down the adjacent vertical sides 7, 7. This slit is cut through the metal before the blank is shaped into the form of the container, and at the same time the metal is preferably scored along 85 the lines 8, 8 in alinement with and continuation of the ends of the slit 5, these scorings preferably extending to the bottom edges of the vertical sides 7, 7 of the container.

The metal strip or taggers tin 9 is secured 90 to the blank to entirely cover the slit 5 by soldering the same along its edges to the blank. One end of the taggers tin is provided with a loop or bent-up flap 10 which is not soldered to the container. The workman 95 runs his soldering iron lightly along one edge of the taggers tin 9, as shown at 11, then along the opposite end of the taggers tin, which is preferably beveled, as shown at 12, and returns along the other side edge 100 of the taggers tin, the soldering iron being passed across the taggers tin below the end of slot 5 and adjacent to the flap 10, to sweat the solder across strip 9 at this point. The end 12 of the strip is preferably beveled, as 105 stated, to facilitate the soldering iron passing around the taggers tin at its end without leaving a considerable mass of solder,

which would make the opening of the package more difficult.

The container being filled with biscuits 13, for example, the opening of the same is 5 readily effected by outward pull on flap 10, whereupon the taggers tin is entirely removed. The container then being held on opposite sides of the slit 5, downward pressure on the two end portions results in the 10 metal easily opening along the scored lines 8, 8, the two halves of the container swinging open about the line 14 as a hinge, the line designated 14 extending across the bottom side of the container between the lower 15 ends of the scored lines 8, 8. Preferably, there is no scoring along the geometrical line 14, so that the two halves of the container swing open about this line as a hinge without separating entirely, as shown.

20 While the container has been described as of rectangular section, it will, of course, be obvious that it may be of circular, triangular, or other desired section, in which cases the slit 5 (and scored lines 8 if used) will 25 extend for suitable distances, so that an unbroken line or portion of the metal will remain, about which the two end portions of the container may swing open, as described.

What we claim is:—

30 1. A container for food products, comprising an elongated continuous casing, en-

tirely closed and tight when filled, having a slit extending partway around the same, intermediate its end portions, and a thin strip secured along its edges to the casing 35 to cover said slit, said strip having an unattached end by which the strip may be pulled off, and said casing being adapted to swing open about a line in alinement with said slit, when pressure is applied on opposite sides of said slit.

2. A container for food products, comprising a casing, entirely closed and tight when filled, having a slit extending partway around the same, between its end portions, 45 and having lines scored thereon in continuation of said slit, for part of the remainder of the periphery of the casing, and a thin strip secured to said casing to cover said slit, said strip having an unattached end by 50 which the strip may be pulled off, and said casing being adapted to swing open along a line in alinement with said slit and scoring, when pressure is applied on opposite sides of said slit.

This specification signed and witnessed this 18th day of June, 1918.

ROY E. TOMLINSON.

HENRY H. HUNGERFORD.
